UNITED STATES PATENT OFFICE.

JACOB LOOPO, OF NEW YORK, N. Y.

LACE.

Application filed January 5, 1925. Serial No. 716.

This invention relates to improvements in lace and I would have it distinctly understood that in employing this term "lace" I use it in the broadest possible sense to include embroidery and other analogous open-work material.

Furthermore, my invention particularly relates to lace, embroidery, etc., which is machine made upon standard types of machine and has to do with the formation of the lace which receives a draw string.

An object of the invention is, therefore, to provide lace with an improved arrangement of draw string receiving loops, certain of the loops being omitted, preferably at regular intervals, whereby spaces are provided between groups of loops, and when the draw string is operated the lace can be gathered or shirred without leaving a rumpled or uneven surface or edge for attachment with other material, or for properly positioning the lace around the neck or arm.

In other words, my invention has to do with lace which is so constructed that the latter may be given the desired arc or curvature by means of the draw string.

With these and other objects in view, the invention consists in certain novel features of construction, and combinations and arrangements of parts, which will be more fully hereinafter described and pointed out in the claim.

In the accompanying drawings—

Figure 1 illustrates, on a somewhat exaggerated scale, a piece of lace or embroidery having my improvements thereon;

Figure 2 is a plan view, more or less diagrammatic, showing how the lace or embroidery may be gathered or shirred to give it the desired curvature;

Figure 3 is a fragmentary exaggerated view illustrating a modification.

As above stated, my improved lace or embroidery is made upon a standard type of machine, and it is to be distinctly understood that the invention has nothing to do with the particular design of the lace or embroidery as this may be varied without limit.

Referring particularly to Figures 1 and 2, 50 1 represents a piece of lace and 2 what is

known in the art as a "steel", which constitutes a covered thread and normally forms the finishing edge of the lace.

On this steel I provide a series of loops 3 which are suitably interlocked or tied in the 55 steel and which receive a draw string 4.

It will be noted that the loops 3 are arranged in groups with loops omitted between the groups, leaving spaces, and it is preferable that this arrangement of groups 60 of loops and the length of spaces be uniform so that when the string 4 is drawn the series of loops will be moved toward each other and the lace or embroidery will be of the desired curvature or what is known in 65 the art as gathering or shirring, and at the same time leave a smooth, unruffled edge, as indicated in Figure 2.

In Figure 3 I illustrate a modification in which the same general idea is carried out 70 to permit gathering or shirring intermediate the edges of the lace. With this idea in view two sections of lace 5 and 6 are each provided with a longitudinal series of spaced loops so that the draw string 8 projected 75 through the loops can gather or shirr the material.

It is this broad idea of providing draw string loops, with certain of the loops omitted to permit a smooth gathering or 80 shirring, which constitutes the broad idea of my invention, and I do not wish to be limited to any particular manner of forming the loops nor of making the lace, although it is to be understood that in forming the lace I may employ a standard type 85 of machine which will carry out the operation of producing the lace as above defined.

While I have illustrated the draw string as a cord, it is obvious that a tape or string 90 of any desired thickness and transverse dimension may be employed, it being understood, of course, that the loops will be made of the proper size to receive the particular draw string or tape desired.

Various slight changes and alterations might be made in the general form of the parts described without departing from my invention, and hence I do not limit myself 95 to the precise details set forth but consider 100

myself at liberty to make such slight changes and alterations as fairly fall within the spirit and scope of the appended claim.

I claim:

5 As a new article of manufacture, lace, draw string securing loops forming a part of the lace and said loops arranged in sets,

each set composed of a plurality of closely associated loops the loops running transversely of the plane of the lace, the sets of loops spaced apart, and a draw string extending through the sets of loops and across the gaps between the sets of loops.

JACOB LOOPO.
